SPARK ARRESTER

Courtney F. Russell, Rochester, Ind., assignor of
one-half to James M. McCarty, Rochester,
Ind.

Application April 12, 1934, Serial No. 720,268

10 Claims. (Cl. 183—97)

The invention relates to spark arresters, and has for its object to provide a device of this character which will effectively trap and extinguish sparks issuing from a chimney without lessening the efficiency of the chimney.

A further object is to provide a device of this character having novel means for mounting it on a chimney.

A further object is to provide a device of this character with a novel supporting and reinforcing member.

A further object is to provide a device of this character with an open ended screen member whose sides comprise a plurality of relatively angularly disposed portions which increase the area thereof without decreasing the efficiency of the chimney.

With the above and other objects in view, the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a top plan view of the device illustrating the outer screen member cut away on line *a—a*.

Figure 2 is a view of the device in side elevation illustrating the outer screen member cut away on line *b—b*.

Figure 3 is a fragmentary perspective view of the outer screen member.

Figure 4 is a perspective view of the base of the inner screen member.

Referring to the drawing, which illustrates the preferred embodiment of the invention, the numeral 5 designates a chimney, on the upper end of which the spark arrester is adapted to be mounted.

The spark arrester comprises an outer member 6 and an inner member 7. Outer member 6 comprises a plurality of vertical side members 8 and a top member 9, all of which are formed of a suitable metal or wire screen. A heavy metal or wire bar 10 is bent to a configuration (preferably rectangular) conforming to but larger than the configuration of the lower end of member 6, the ends of said bar 10 being angularly outwardly extended at 11. The lower ends of the sides 8 of the outer member 6 are disposed within and bent around bar 10 to secure said bar thereto, although the same may be secured in any suitable or desired manner; and bar 10

thus forms a supporting and reinforcing frame for outer member 6. At each of its sides the frame bar 10 is provided with an upwardly directed intermediate off-set portion 12, for purposes to be hereinafter set forth. A plurality of vertical plates 13 are secured to each of the sides 8 of member 6 to project below frame 10. Plates 13 extend within member 6 and bear against the sides 8 thereof, and are secured to place by bolts 14 which pass therethrough and through the screen and a suitable washer or plate 15 which bears on the screen side member 8 exteriorly thereof. The projecting lower ends of the plates 13 engage the outer sides of chimney 5 and are preferably secured to said chimney by bolts 16 to support said outer member 6 in operative relation thereto with the frame 10 disposed substantially in the plane of the upper end of the chimney and off-sets 12 thereof disposed above the upper end of the chimney.

The inner member 7 of the device comprises a rectangular base 17, preferably formed of sheet metal, which is disposed in face contacting engagement with the upper face or end of chimney 5. Base 17 has a central opening therein of a size and shape conforming substantially to that of the chimney opening, which base opening is defined by angularly upwardly and inwardly directed flanges 18. A screen member 19, of general rectangular plan outline, is fixedly secured to base 17 and flanges 18 by soldering or other suitable means. Member 19 is formed of a shape wherein its sides taper inwardly and upwardly at 20, thence outwardly and upwardly at 21, thence inwardly and upwardly at 22, and terminate in outwardly and upwardly directed portions 23. Member 19 is open at both of its ends, and its upper end is spaced below top member 9 of outer member 6 when the device is operatively positioned on the chimney. The lateral dimensions of member 19 are less than of member 6 at all points thereof, whereby said member is spaced inwardly of said member 6 at all sides thereof. The major portion of the inner screen member 19 is disposed inwardly of a vertical projection of the inner edges of base 17 and of the inner faces of the walls of the chimney.

In its use, the device serves to arrest passage of sparks issuing from the chimney, the inclined sides of screen member 19 serving, when wind 50 blows sparks and soot thereagainst, to stop or catch the same, while the top 9 of outer member 6 serves the same purpose where the sparks or soot are not directed against or caught by the sides of member 19. Soot may also pass up- 55

wardly through member 19 and then downwardly between member 19 and sides 8 of outer member 6 and out beneath the off-set 12 of frame 10; this same passage through the device to the atmosphere assuring the necessary chimney draft at all times, whereby chimney efficiency will not be lowered by the device when the same has collected large amounts of soot thereon. The off-set 12 also provides a passage between outer member 6 and the chimney through which wind may pass to clean the device of soot collected thereon. The extended end portion 11 of bar frame 10 may be connected with a suitable electrical conductor 25 leading to the ground, whereby the device serves as a lightning conductor as well as a spark arrester.

The invention having been set forth, what is claimed as new and useful is:

1. A spark arrester adapted to be mounted on a chimney, comprising a frame adapted to be supported by the upper end of the chimney and having an opening therein substantially similar to and coinciding with the opening of the chimney, an open ended screen carried by said frame adjacent the inner edges thereof, said screen member including portions extending angularly relative to the vertical and inwardly of a vertical projection of said frame opening, and an outer screen member carried by the chimney and including sides and a top spaced from said inner member.

2. A spark arrester adapted to be mounted on a chimney, comprising an open ended screen member adapted to be mounted on the chimney, an outer screen member including sides and a top spaced from said first named member, a frame of a size larger than said outer member, the lower ends of the sides of said outer member being bent around said frame, and means for securing said outer screen to said chimney.

3. A spark arrester adapted to be mounted on a chimney, comprising an open ended screen member adapted to be mounted on the chimney, an outer screen member including sides and a top spaced from said first named member, a frame of a size larger than said outer member, the lower ends of the sides of said outer member being bent around said frame, and means for securing said outer screen to said chimney including a plurality of pairs of plates, one plate of each pair being disposed interiorly and the other exteriorly of said outer screen member, and means for securing said plates together in bearing engagement with said screen member; said plates disposed plates projecting below said frame for engagement with the sides of said chimney.

4. A spark arrester adapted to be mounted on a chimney, comprising an open ended screen member adapted to be mounted on the chimney, an outer screen member including sides and a top, a frame secured to the sides of said outer member at their lower ends, said frame including upwardly off-set portions, and means for mounting said outer member on the chimney with said frame off-sets positioned above said chimney and the sides and top thereof spaced from said first named member.

5. A support for a combined spark arrester and lightning conductor adapted to be mounted

on a chimney, comprising a bar bent intermediate its ends in rectangular shape to form a supporting frame for the spark arrester, the ends of said bar projecting outwardly of said frame in contacting engagement for connection with a lightning conductor.

6. A support for a combined spark arrester and lightning conductor adapted to be mounted on a chimney, comprising a bar bent intermediate its ends to a shape similar to that of the top of the chimney to form a supporting frame for the spark arrester, said frame portion being provided with upward off-sets adapted to be positioned above the top of the chimney, the ends of said bar projecting laterally outwardly of said frame in contacting engagement for connection with the lightning conductor.

7. A spark arrester adapted to be mounted on a chimney, comprising an inner open ended screen member, a base for said member extending outwardly thereof and supported by the top face of the chimney, said member having sides comprising portions positioned alternately in angularly inwardly and angularly outwardly extending relation to the vertical, and an outer screen member having sides and a top spaced from said inner member, a frame supporting said outer member and including upwardly off-set portions, and means for securing said outer screen to the chimney to position said off-set portions above said chimney and said outer member in spaced relation to said inner member.

8. A spark arrester adapted to be mounted on a chimney, comprising an inner open ended screen member adapted to be mounted on the chimney, the sides of said member including a plurality of portions each positioned angularly relative to the adjacent portions and to each other, an outer screen member having sides and a top spaced from said inner member, each side of said outer member having an upward off-set at its lower edge, and means for securing said outer member to the chimney with said off-sets positioned above said chimney.

9. A spark arrester adapted to be mounted on a chimney, comprising an outer screen member adapted to be mounted on the chimney and including sides and a top, and an open ended screen member adapted to be mounted on the chimney independently of the outer member and disposed in spaced relation to and within said outer screen member, said inner member including a plurality of sides each comprising a plurality of portions extending in alternately inwardly and outwardly angular relation to the vertical, at least part of each of said side portions extending inwardly of a vertical projection of the mouth of the chimney.

10. A spark arrester adapted to be mounted on a chimney, comprising a screen member having sides and a top, and a second screen member disposed in said first member in inwardly spaced relation thereto, said second member being open at its upper and lower ends and the walls thereof comprising integral longitudinally spaced portions whereby said second member has alternate enlarged and restricted perimeters relative to the average perimeter thereof.
